United States Patent Office

Des. 231,404
Patented Apr. 16, 1974

231,404

LABEL APPLICATOR

Rollin H. Sontag, Kings Point, N.Y., assignor to Joan S. Sontag, Kings Point, N.Y.

Filed Nov. 2, 1972, Ser. No. 303,267

Term of patent 14 years

Int. Cl. D18—99

U.S. Cl. D64—10

FIG. 2

FIG. 5

FIG. 3

FIG. 1

FIG. 4

FIG. 1 is a perspective view of a label applicator showing my new design;

FIG. 2 is a top plan view thereof;

FIG. 3 is a rear elevational view thereof;

FIG. 4 is a left side elevational view thereof; and

FIG. 5 is a front elevational view thereof.

I claim:

The ornamental design for a label applicator, substantially as shown.
